UNITED STATES PATENT OFFICE.

ARTHUR ROSENTHAL, OF GRAND RAPIDS, MICHIGAN, ASSIGNOR TO ROSE LABEL
MACHINE COMPANY, OF GRAND RAPIDS, MICHIGAN.

SEWING-MACHINE FOR ATTACHING LABELS.

1,111,494.

Specification of Letters Patent. Patented Sept. 22, 1914.

Application filed March 11, 1912. Serial No. 683,068.

To all whom it may concern:

Be it known that I, ARTHUR ROSENTHAL, a citizen of the United States, residing at the city of Grand Rapids, county of Kent, 5 and State of Michigan, have invented certain new and useful Improvements in Sewing-Machines for Attaching Labels, of which the following is a specification.

This invention relates to improvements in 10 sewing machines for attaching labels or patches or for reinforcing or similar work.

The objects of the invention are: First, to provide in a machine of this class an improved means to hold and guide the label or 15 work while it is being sewed. Second, to provide improved feed means and guide means for feeding the work to the sewing machine needle. Third, to provide an improved actuating means for a label attaching 20 or similar sewing device. Fourth, to provide an improved adjustable means to adapt the machine to attach different sizes of labels. Fifth, to provide an improved construction 25 of presser foot which readily adjusts itself to the work and which puts tension on the fabric being sewed.

Further objects, and objects relating to 30 details and economies of construction and operation will definitely appear from the detailed description to follow.

The objects of this invention are accomplished by the machine described in the following specification.

The invention is clearly defined and 35 pointed out in the claims.

A machine constituting a preferred embodiment of the invention is fully illustrated in the accompanying drawing, forming a part of this specification, in which:

40 Figure I is a perspective view of a sewing machine embodying the improved label attaching and sewing device. Fig. II is a detail perspective in miniature of the back side of the sewing machine arm, showing 45 the lever and connections for elevating the presser foot. Fig. III is an enlarged detail plan view, portions of the sewing machine plate being broken away, of the improved label attaching device and the actuating 50 mechanism, the sewing machine arm and head being omitted. Fig. IV is a detail sectional view, some portions being broken away, taken on a line corresponding to line 4-4 of Fig. III. Fig. V is an enlarged

detail perspective view of the ratchet and 55 pinion for actuating, feeding and controlling the movement of the actuating lever frame, the same being detached and inverted. Fig. VI is an enlarged perspective view of the actuating lever frame, showing 60 the adjustment of the toothed rack sections and other associated parts. Fig. VII is an enlarged detail sectional view taken on a line corresponding to line 7-7 of Fig. IV, showing details of the swivel pivot slide on 65 which the actuating lever frame oscillates and slides. Fig. VIII is an enlarged detail perspective view of the detent pawl structure for the feed ratchet wheel. Fig. IX is an enlarged detail plan view of the cam 70 plate, showing both surfaces, for controlling and guiding the lever actuating frame, the cam guide and its rollers being shown in position, the view being taken on broken line 9-9 of Fig. IV. Fig. X is an inverted 75 plan view of the cam guide means for engaging the cam surfaces, the position in relation to the cam being indicated by dotted lines. Fig. XI is an enlarged detail transverse sectional view through the presser foot 80 or work holder taken on a line corresponding to the section line 4-4 of Fig. III, showing the adaptability and adjustability of such work holder. Fig. XII is a detail sectional view on line 12-12 of Figs. III 85 and XI showing details of the work holder. Fig. XIII is a detail sectional view on line 13-13 of Fig. XI showing the flexible connections of the serrated side bar of such work holder. Fig. XIV is an enlarged detail perspective view of a modified and simple form of my improved pressure foot 90 or work holder and details of attachment to the arm of the actuating lever frame structure.

95 In the drawing, similar numerals of reference refer to similar parts throughout the several views, and the sectional views are taken looking in the direction of the little arrows at the ends of the section lines.

100 Considering the numbered parts of the drawing, the plate 1, arm 2, head 3, needle bar 4 and needle 5 are in the usual form for sewing machines, and the machine is driven in the way that is common and well known for power driven sewing machines, although my invention may be used on treadle machines. The details of these parts, therefore,

are not gone into and are not illustrated as they are of a usual well known form. This invention is associated with and is an addition to these parts, the same being principally secured to the plate 1, although it is connected to and operated by other parts of the machine.

The presser foot 6 comprises a frame structure, the side portions of which are provided with yielding contact face bars 8 serrated at 8' on their contact surfaces and provided with upwardly projecting guide portions 9 at the tops, which are engaged in suitable guide recesses 10 in the sides of the said presser foot frame. These bars are retained in position by screw 11 which plays freely in the frame, and extends down into the upper surface of the said bar, the head of the screw being countersunk into the frame, which serves as a stop to limit the downward movement. Compression springs 12-12 in suitable recesses at each end of the face bar 8 serve to hold the same yieldingly in position so that even pressure is secured on the face bars from end to end, and owing to the character of these supports work of varying uneven thickness can be readily held by the same and the same can be effectively stitched. At the front side and rear side of this frame are laterally yielding members 16-16, the lower edges of which coincide with the lower face of the presser foot. These parts are carried on extensions 15-15 of the flat blade springs 13 extending within the frame and outwardly at each side of the arm 7, being secured thereto by screws 14.

Beneath the presser foot is a clamp plate 74 having an aperture 77 corresponding to the opening of the presser foot. This plate 40 is curved upwardly at 75 and then rearwardly, and is secured to the forward end of the oscillating lever 38 by screws 76 (see Figs. IV and VI). This plate 74 rests upon the work plate of the sewing machine and 45 passes freely over the same when the label is being passed to the needle. This clamp plate 74 may be dispensed with and the goods allowed to slip over the work plate of the sewing machine. For most work, however, the 50 plate is a very satisfactory device, as it insures the delivery of the work in the best possible form without danger of wrinkling or wear, and at the same time, the clamp plate 74 protects the work plate of the sewing machine from injury so that the smooth 55 surface is always insured for the movement of the work in the machine. In Fig. XIV, I show this presser foot greatly simplified and in a form that is preferred where regular work is being done which is always of an even thickness such as affixing labels to napkins or tablecloths, for instance. In this 60 figure the presser foot is shown in inverted perspective, so that the parts can be readily seen. The presser foot is made up of front

and rear bars 83 suitably spaced to engage the fabric, and the yieldable end members 84-84 are formed integral with the springs 13-13 which are extended downwardly for that purpose. These springs are secured to the arm 7 by the screws 14 as before, as clearly appears from an inspection of Fig. XIV.

The arm 19 is secured to the actuating lever frame 20 by hinged member 21 engaging a pivot pin 22, the said hinged member being secured to the frame 20 by screws 23, or other suitable means (see particularly Figs. III, IV and VI). This permits the presser foot 6 to be elevated by swinging upon the said hinge. The arm 19 is held down by spring pressure by means of the coiled spring 24 on the vertical rod 25 secured to the needle end of the frame 20, the tension of said spring being adjustable by the thumb nut 26. These parts are carried by a base plate 27, which is secured to the machine plate 1 by clamp screws 28 in the slots 29 thereof (see Figs. I and III), the same being detailed particularly in Fig. III. This describes the structure as an attachment. The device might be incorporated and made integral with the main casing.

The actuating lever frame 20 is carried upon an adjustable fulcrum or swivel 30 which is clamped in a slot 31 of the base plate 27. A projection 32 engages in a top groove 33 at each side of the slot and a hexagon nut 34 engages a bottom groove 35 at each side, whereby this fulcrum pivot can be very readily adjusted. A slide 36 is pivoted on this fulcrum and is retained in its place by the shouldered screw 37 above the same, so that the actuating lever frame 20 plays freely back and forth on this slide, which is located in the ways 38 formed thereon, so that the actuating lever frame 20 has a swivel action on the pivot 30, and at the same time slides freely back and forth on slide 36, permitting its movement to be universal and under complete control.

The actuating lever frame 20 is driven by the ratchet wheel 39 which is carried on a suitable hub projection from the axis of the pinion 39'. The pinion 39' is supported on the pointed bearings 40 and 42, the bearing 40 being screw threaded into the base plate and locked in position by the lock nut 41, and the bearing 42 being supported by the supporting arm 43. It is screw threaded therein, and lock nut 44 is provided for locking the same in position. A vertical oil hole 45 is through the entire bearing parts whereby the same can be effectively lubricated.

The ratchet wheel 39 is actuated by the pawl 47 carried on the pin 48, in yoke 46, which is pivoted on the axis of the pinion 39'. A spring 49 holds the pawl in engagement with the ratchet wheel. The pin 48

terminates in a ball 50, which is one member of a ball and socket joint, by which the link 52 is connected thereto. The rock shaft arm 51 is connected by the link 52 to the pin 48. The link 52 is connected by ball and socket joints 53—53 at each end. The rock shaft arm 51 is carried upon the feed rock shaft 54. Any rock shaft connected to the driving mechanism of the sewing machine will serve the same purpose. By this means it will be noted that whenever the feed shaft is rocked, the ratchet wheel is advanced and the mechanism provided is operated. The right hand end of the actuating lever frame 20 comprises a rack and pinion structure by which this feed device is operated for feeding the labels to the needle. A straight rack 58 with suitable teeth thereon is disposed toward the back of the frame, and is held in place by set screws 59. A straight rack 60 parallel therewith is at the front of the frame, and is retained in position by set screws 61. A curved rack 62 is toward the left or the needle end of this frame, and a corresponding curved rack 63 is on the opposite side thereof. These are clamped between the racks 58 and 60, the ends of these racks 62 and 63 being formed with gear teeth that exactly mesh with the gear teeth of said rack whereby they are adjustable back and forth, and are retained in correct operative relation. Because these are adjustable on the gear teeth, whenever they are adjusted the pinion which actuates the same meshes with the gears without further fitting or adjusting. A cam structure is provided for guiding this actuating lever frame, so that the presser foot 6 will be correctly guided and the label fed in proper manner to the sewing machine needle to be stitched. A guide device for engagement with the cam is provided at the right hand end of the actuating lever frame. This guide device comprises a disk 66 on the lower end of journal pin 67, which is retained in place by shouldered screw 68. A roller 64 to contact with the main cam guide surface to follow the surface thereof is carried upon a journal pin 65 which projects downwardly from the disk 66. To insure proper engagement of the guide roller 64 at all times with the cam, a supplemental guiding cam surface 72 is provided, over which a supplemental guiding roller 70 passes. This roller is borne on a pivot 71 on the disk 66.

The principal or lower cam surface 69 is disposed on the base plate 27 on the edge of which the guide roller 64 travels, as will be seen from an inspection of Figs. X and IX. On top of this main cam 69 is the supplemental guiding cam surface 72, having projections 73 at each corner, which engage the supplemental roller 70 and retard the travel of the main roller until it correctly turns

the corner. Owing to the fact that these rollers are both carried upon the same pivot plate, the auxiliary roller 70 becomes disengaged from the said projection, owing to the pivoting thereof, and permits the travel 70 around the same. The cam plates are made integral and are secured in place by the attaching screws 69.

The presser foot is elevated by suitable connecting rod 82 to a treadle or foot lever 75 or other device not shown. This connecting rod 82 is connected to lever 80 which is fulcrumed at 81 on the back side of the arm of the sewing machine and is provided with a lateral extension 79 which is connected by 80 a cable connection 78 to the presser foot lever 19, as clearly appears in detail in Figs. I, III and IV.

From this description of the parts, the operation of the device is clear. The presser foot 6 is elevated. The yielding ends 16—16 thereof are pressed toward each other by the grasp of the operator, the foot is then let down upon the label or other work and the compressed parts 16—16 are allowed to separate, thereby putting tension upon the label or work and smoothing it out perfectly smooth and flat upon the clamp plate 74 or on the work plate of the sewing machine. This raising and lowering of the presser foot is accomplished by depressing the foot control through the connection 82, which raises the presser foot 6. The machine is started and very rapidly and automatically feeds the label or other work to the needle, 100 owing to the step-by-step action of the ratchet of the automatic feed. The feed ratchet is operated at every oscillation of the arm 51 by the feed shaft or other oscillating or rocking part of the machine. The 105 cam plates at the right of the machine are engaged by the guide devices and control the arm to feed the label and give the same exactly the correct movement for placing the line of stitches in the edge of the label 110 as required.

It is very clear that by removing the particular label presser foot, by detaching the same and substituting another size, and readjusting the rack and substituting a cam plate 115 of proper dimension, any size or form of label within the capacity of the machine can be very readily stitched and attached in this way.

The various parts of this label attaching mechanism may be greatly varied and modified without departing from the invention. The presser foot is capable of use with any suitable actuating means. The actuating means can be greatly modified and is capable of use with any suitable presser foot. 120

It is desired to claim the invention specifically, because the particular form illustrated has great merit, and it is also desired to claim the invention broadly, as pointed out in the appended claims. 125

Having thus described my invention, what I claim as new and desire to secure by Letters Patent is:

1. In a label attaching machine, the combination with the bed, arm, head, needle bar and driving means of a sewing machine, of a supporting plate secured to the bed of said machine, an actuating lever frame structure carried thereby comprising a gear toothed frame part with inwardly projecting gear teeth; a swivel slide on the said supporting plate engaging in suitable ways on the said actuating lever frame; a presser foot carrying arm hinged to the said actuating lever frame; a suitable spring for putting pressure thereon, a presser foot comprising a frame with corrugated under surfaces and spring supported yielding end bars compressible inwardly whereby the said end bars are adapted to engage a label when placed beneath the same and put tension thereon so that the needle of the sewing machine can stitch within the border thereof to attach the label; a ratchet feed device; a pinion driven by said ratchet feed adapted to mesh with the gear toothed frame part of said actuating lever frame; a cam plate on said base; and a cam engaging guide member carried by said actuating lever frame for guiding and controlling the motion of the feed device, all coacting substantially as described and for the purpose specified.
2. In a label attaching machine, the combination with the bed, arm, head, needle bar and driving means of a sewing machine, of a supporting plate secured to the bed of said machine; an actuating lever frame structure carried thereby comprising a rectangular gear toothed frame part made up of rack bar members with inwardly projecting gear teeth adjustable in their relations to each other by suitable gear toothed engaging portions; a swivel slide on the said supporting plate engaging in suitable ways on the said actuating lever frame; a presser foot conformed to the label to be attached; a feed device for the actuating lever frame consisting of a ratchet wheel with suitable support; a ratchet pawl for actuating the same with connections therefor to a moving part of the machine for advancing the presser foot and carrying a label to the needle of the sewing machine; a pinion driven by said ratchet wheel adapted to mesh with the gear toothed frame part of said actuating lever frame; a cam plate on said supporting plate; and a cam engaging guide member carried by said actuating lever frame for controlling the motion of the feed device, all coacting substantially as described and for the purpose specified.
3. In a label attaching machine, the combination with the bed, arm, head, needle bar and driving means of a sewing machine, of a supporting plate secured to the bed of said machine; an actuating lever frame structure carried thereby comprising a gear toothed frame part with inwardly projecting gear teeth; a swivel slide on the said supporting plate engaging in suitable ways on the said actuating lever frame; a presser foot conformed to the label to be attached; a feed device for the actuating lever frame consisting of a ratchet wheel with suitable support; a ratchet pawl for actuating the same with connections therefor to a moving part of the machine for advancing the presser foot and carrying a label to the needle of the sewing machine; a pinion driven by said ratchet wheel adapted to mesh with the gear toothed frame part of said actuating lever frame; a cam plate on said base with a main cam surface and an auxiliary cam surface with retarder projections at the angles; and a cam engaging guide member carried by said actuating lever frame for controlling the motion of the feed device, comprising a swiveled plate with contact rolls to engage said cam actuating surfaces, all coacting substantially as described and for the purpose specified.
4. In a label attaching machine, the combination with the bed, arm, head, needle bar and driving means of a sewing machine, of a supporting plate secured to the bed of said machine; an actuating lever frame structure carried thereby; a swivel slide on the said supporting plate engaging in suitable ways on the said actuating lever frame; a presser foot carrying arm hinged to the said actuating lever frame; a suitable spring for putting pressure thereon; a presser foot comprising a frame with corrugated under surfaces and spring supported yielding end bars compressible inwardly whereby the said ends are adapted to engage a label when placed beneath the same and put tension thereon so that the needle of the sewing machine can stitch within the border thereof to attach the label; and a feed device for the actuating lever frame, for the purpose specified.
5. In a label attaching machine, the combination with the bed, arm, head, needle bar and driving means of a sewing machine, of a supporting plate secured to the bed of said machine; an actuating lever frame structure carried thereby; a swivel slide on the said supporting plate engaging in suitable ways on the said actuating lever frame; a presser foot comprising a frame with yielding face bars having corrugated under surfaces and spring supported laterally yielding end bars compressible inwardly between the ends of said frame whereby the said end bars are adapted to engage a label when placed beneath the same and put tension thereon so that the needle of the sewing machine can stitch within the border thereof to attach the label.

the label; a clamp plate having an opening corresponding to the opening of said presser foot disposed beneath said presser foot and coöperating therewith to hold the work; and 5 a feed device for the actuating lever frame, for the purpose specified.

6. In a label attaching machine, the combination with the bed, arm, head, needle bar and driving means of a sewing machine, of 10 a supporting plate secured to the bed of said machine; an actuating lever frame structure carried thereby; a swivel slide on the said supporting plate engaging in suitable ways on the said actuating lever frame; a presser 15 foot comprising a frame with yielding face bars having corrugated under surfaces and spring supported laterally yielding end bars compressible inwardly between the ends of said frame whereby the said end bars are 20 adapted to engage a label when placed beneath the same and put tension thereon so that the needle of the sewing machine can stitch within the border thereof to attach the label; and a feed device for the actuating 25 lever frame, for the purpose specified.

7. In a label attaching machine, the combination with the bed, arm, head, needle bar and driving means of a sewing machine, of 30 a supporting plate secured to the bed of said machine; an actuating lever frame structure carried thereby; a swivel slide on the said supporting plate engaging in suitable ways on the said actuating lever frame; a presser 35 foot comprising side and end bars, a part of which are compressible to put tension on a label; a clamp plate having an opening corresponding to the opening of said presser foot disposed beneath said presser foot and coöperating therewith to hold the work; and 40 a feed device for the actuating lever frame, for the purpose specified.

8. In a label attaching machine, the combination with the bed, arm, head, needle bar and driving means of a sewing machine, of

a supporting plate secured to the bed of said 45 machine; an actuating lever frame structure carried thereby; a swivel slide on the said supporting plate engaging in suitable ways on the said actuating lever frame; a presser foot comprising side and end bars, a part of 50 which are compressible to put tension on a label; and a feed device for the actuating lever frame, for the purpose specified.

9. In a machine of the class described, the combination of a presser foot formed with 55 an opening said presser foot comprising a frame with yielding face bars having corrugated under surfaces and spring supported laterally yielding end bars compressible inwardly between the ends of said frame 60 whereby the said end bars are adapted to engage a label when placed beneath the same and put tension thereon so that the needle of the sewing machine can stitch within the border thereof to attach the label; and a 65 clamp plate having an opening corresponding to the opening of said presser foot disposed beneath said presser foot and coöperating therewith to hold the work, as specified. 70

10. In a machine of the class described, the combination of a presser foot comprising a frame with corrugated under surfaces and laterally yielding end bars compressible inwardly and vertical blade spring supports 75 for said end bars whereby the said end bars are adapted to engage a label when placed beneath the same and put tension thereon so that the needle of the sewing machine can stitch within the border thereof to attach 80 the label, as specified.

In witness whereof, I have hereunto set my hand and seal in the presence of two witnesses.

ARTHUR ROSENTHAL. [L. S.]
